DESIGN FOR A CONFECTIONERY DISPENSING MACHINE

Lauritz Petrus, New York, N. Y.

Application November 29, 1947, Serial No. 142,887

Term of patent 7 years

(Cl. D52—3)

To all whom it may concern:

Be it known that I, Lauritz Petrus, a citizen of the United States of America, residing at New York city, in the county and State of New York, have invented a new, original, and ornamental Design for a Confectionery Dispensing Machine, of which the following is a specification, reference being had to the accompanying drawing, forming part thereof.

Fig. 1 is a front elevation of a confectionery dispensing machine showing my new design;

Fig. 2 is a side view of the right hand side;

Fig. 3 is a top view, and

Fig. 4 is a rear view.

The side of the machine not disclosed is the same in appearance as the side shown, except for details.

I claim:

The ornamental design for a confectionery dispensing machine, substantially as shown and described.

LAURITZ PETRUS.
